UNITED STATES PATENT OFFICE.

FRANK H. DANIELS, OF PHILADELPHIA, PENNSYLVANIA, ASSIGNOR TO JOHN M. ROGERS WORKS, INC., OF GLOUCESTER CITY, NEW JERSEY, A CORPORATION OF NEW JERSEY.

ADJUSTABLE LIMIT-GAGE.

1,367,537.

Specification of Letters Patent.

Patented Feb. 8, 1921.

Application filed June 5, 1919. Serial No. 301,868.

To all whom it may concern:

Be it known that I, FRANK H. DANIELS, a citizen of the United States, residing at Philadelphia, county of Philadelphia, and 5 State of Pennsylvania, have invented a new and useful Improvement in Adjustable Limit-Gages, of which the following is a full, clear, and exact description, reference being had to the accompanying drawings, 10 which form a part of this specification.

A well known form of adjustable limit gage comprises a yoke, two axially adjustable pins on the inside of one arm of the yoke and opposing similar pins on the other 15 arm of the yoke. These pins are so adjusted that two opposing pins measure a distance slightly exceeding the desired measurement of the work, while the other pair of pins measures a distance slightly less 20 than the desired measurement of the work. Gages may also be made with a single pair of adjustable pins, one at one end of the yoke, the opposing one at the other end of the yoke. One or both pins of a pair may 25 be made adjustable.

It is necessary, after the pins are adjusted, that they should be restrained from the slightest movement in an axial direction. It is also desirable that the adjustment 30 should not be effected by turning the pins in their sockets, because, if the end faces of the pins are not exactly at right angles with their axes or if the axes of the two bolts are not precisely coincident, the turning of 35 the pins will destroy the exactitude of the gage.

The object of the invention is to provide means for securely locking the gage pins in their adjusted positions while preventing 40 any substantial turning movement of the pins.

Figure 1 is a front elevation of the tool.

Fig. 2 is a side view of one of the heads of the yoke and the gage pins and adjusting 45 means carried thereby.

Fig. 3 is a cross-section on line 3 of Fig. 2.

Fig. 4 is a section on line 4—4, Fig. 2.

The yoke *a* is provided with two sockets 50 in each end head for the reception of the pins *j*. Each pin projects beyond the inner end of the socket and terminates short of the other or outer end of the socket. The

outer end of the socket is somewhat enlarged and is internally threaded for the reception 55 of an adjusting screw *c*, which abuts against the pin *j*. Each pin is provided with a groove *d* whose side walls are parallel to a radius of the pin. Inset in the frame of the yoke are two push rods *h*, *h*, which extend 60 at right angles to the pins *j* and are provided on their ends with projections *i*, *i*, which enter grooves *d* in the pins. The outer side of one of the pin sockets is cut away to allow the insertion, in a lateral direction, of the push rods before the insertion of the pins, the hole being afterward closed by a plug *h*. After the pins are adjusted, which is accomplished by manipulation of adjusting screws *c*, a tapered plug or 70 wedge *m* is forced between the two push rods *h*, *h*, thus forcing the push rods apart and tightly against the bases of the grooves of the pins, whereby the pins are held from movement in either an axial or rotary direction. The yoke head is provided with a hole in which is threaded a screw *n*, by 75 turning which the plug *m* is operated and retained.

To avoid tampering with the tool to 80 change its adjustment, the recess in the threaded end of a pin socket may be sealed by suitable material.

I am aware that it is old to provide a single clamping member having beveled 85 corners which engage flattened peripheral portions of the two pins of a pair. This construction requires extreme accuracy in that the failure of such member to exactly fit the socket or the failure of the two bevelled corners to coincidentally engage the two flattened surfaces of the pins, or any departure from exact parallelism between the bevels of said member and the flattened faces of the pins, will result in failure to 90 bind one of the pins in its socket or permit a limited turning movement thereof. My construction, wherein there are two independent clamping members *h*, one for each recess, is particularly not dependent upon 100 accuracy of construction for proper operation, in that the lengths of the two members may be both variable and unequal, the wedge *m* being capable of being screwed in to a variable extent and being capable also of 105 sidewise displacement, to the degree re-

quired to cause the projections of members h to be pressed tightly into the grooves of the pins.

Having now fully described my invention, what I claim and desire to protect by Letters Patent is:

1. In an adjustable limit gage, the combination with a holding frame having two spaced apart sockets, of gage pins, two independently movable clamping members located between the gage pins and extending substantially at right angles thereto, and common actuating means to force said clamping members bodily away from each other into clamping engagement with their respective pins.

2. In an adjustable limit gage, the combination with a holding frame having two spaced apart sockets, of gage pins in the sockets provided with longitudinal grooves facing toward each other, independently movable clamping means having projections extending into said grooves and means extending between said clamping members adapted to force them bodily in opposite directions into clamping engagement with their respective pins.

3. In an adjustable limit gage, the combination with a holding frame having two spaced apart sockets, of gage pins, two spaced apart bodily movable clamping members, located between the gage pins and extending substantially at right angles thereto, a wedge located between the clamping members and a screw by which the wedge is actuated to engage both clamping members and move them, in the direction of their extension, into clamping relation with the respective pins.

4. In an adjustable limit gage, the combination with a holding frame having a socket, of a gage pin adjustable in the socket in the direction of its axis, a clamping member, within the frame and extending substantially at right angles to the axis of the pin, said member being bodily movable toward the axis of the socket to effect a binding engagement with the pin, whereby lateral pressure is exerted on the pin to bind it in the socket and prevent it from moving.

In testimony of which invention, I have hereunto set my hand, at Gloucester, N. J., on this third day of June, 1919.

FRANK H. DANIELS.
